US00D571372S

(12) **United States Design Patent** (10) **Patent No.:** **US D571,372 S**
(45) **Date of Patent:** **** Jun. 17, 2008**

(54) **COMMUNICATIONS HUB**

(75) Inventors: **Paul E. Brefka**, Southborough, MA (US); **John D'Arco**, Wilmington, MA (US); **Charles Fendrock**, Sudbury, MA (US); **Michael Williams**, Melrose, MA (US)

(73) Assignee: **Neurometrix, Inc.**, Waltham, MA (US)

(**) Term: **14 Years**

(21) Appl. No.: **29/261,025**

(22) Filed: **Jun. 6, 2006**

(51) **LOC (8) Cl.** **14-02**

(52) **U.S. Cl.** **D14/433**

(58) **Field of Classification Search** **D14/240, D14/242, 356, 358, 363, 365, 367, 370, 432-437, D14/439; D13/147, 164, 123, 133, 146, D13/110, 199, 103, 162, 159, 160, 184; 361/683, 361/684, 686, 724, 735, 737, 752**

See application file for complete search history.

(57) **CLAIM**

The ornamental design for a communications hub, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever.

FIG. 1 is a perspective view of a communications hub;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

1 Claim, 4 Drawing Sheets
